Primary Examiner — Ruth McInroy(74) *Attorney, Agent, or Firm* — Peter L. Olson**CLAIM**

The ornamental design for a helmet bracket connector end, as shown and described.

DESCRIPTION

FIG. 1 is a perspective view of a helmet bracket having arrow indicia showing our new design;

FIG. 2 is a top view thereof;

FIG. 3 is a bottom view thereof;

FIG. 4 is a front view thereof;

FIG. 5 is a rear view thereof;

FIG. 6 is a left side view thereof; and

FIG. 7 is a right side view thereof.

FIG. 8 is an enlarged view of the circled area in FIG. 1;

FIG. 9 is a front view of FIG. 8;

FIG. 10 is a right side view of FIG. 8;

FIG. 11 is a left side view of FIG. 8; and,

FIG. 12 is a top view of FIG. 8.

The details shown in broken lines form no part of the claimed design.
